ADJUSTABLE KNEE REST

Robert L. McDonald and Karl H. Burzlaff, Rochester, N.Y., assignors to Bitter Co., Inc., Rochester, N.Y., a corporation of Delaware

Application April 15, 1957, Serial No. 652,939

10 Claims. (Cl. 311—5)

This invention relates to an improvement in medical examination or operating tables and more particularly to an adjustable knee rest for such tables of the type described in McDonald Patent No. 2,764,459 and assigned to the assignee of the present invention.

In medical examination or operating tables of the type such as described in the above mentioned patent, a detachable knee rest is generally provided on the table to facilitate examination, treatment, or operating by proctologists and the like. The knee rest is supported on a leg rest section and a patient may kneel on the knee rest with the lower front portion of his body below his waist in contact with the leg rest section and with the upper part of his body bent over the top of the leg rest section permitting the proper examination by the physician. The effort is made to locate the patient's body and internal organs by the patient bending at the waist to orient the patient properly for examination by the physician.

It can be readily understood that the variation in leg lengths from patient to patient means that the knee rest must be adjusted along the leg rest section for each patient in order to insure that the patient's body when he bends at the waist will extend comfortably over the top of the leg rest section when the patient is in the kneeling position. In order to avoid moving the patient on and off the knee rest while making the proper adjustment of the knee rest in accordance with the physical proportions of the patient, it is highly desirable that the knee rest be capable of adjustment while the patient is kneeling thereon. Furthermore, often during operating or examination of the patient, it is necessary to shift the patient's position which heretofore could only be accomplished by lowering the table and having the patient dismount from the knee rest. Lifting him manually while the knee rest adjustment is made and the table tilted is in most cases an arduous physical task for the doctor to perform.

Accordingly it is a primary object of this invention to provide a new and improved adjustable knee rest for medical examination or operating tables.

Another object of this invention is to provide a new and improved adjustable knee rest for the leg rest section of an articulated examination table which may be adjustably positioned to the correct height while the patient is supported thereon.

It is a further object of this invention to provide a new and improved detachable and adjustable knee rest for an articulated examination or operating table of the type used particularly by proctologists which may be readily moved to a selected position while the patient is supported on the table either preceding or during the examination, operation, or treatment whereby the patient is accurately positioned in the exact position required by the doctor.

In the medical examination or operating tables of the type discussed above wherein a knee rest is employed as a component of the table, the usefulness and adaptability

2

of the table is further improved by providing a knee rest which may be moved so as to lie substantially in the same plane as the table section or sections to thus increase the overall length of the table and adapt it for general office purposes. Such an improvement has been suggested previously, as disclosed in the above patent. However, the usefulness of the table and the easing of the doctor and nurse's task is materially improved by incorporating such a feature in an adjustable knee rest.

10 It is, therefore, a still further object of this invention to provide a new and improved adjustable knee rest for an examination table which is readily adjustable throughout a selected range; which may be quickly and easily detached from the table when it is temporarily not needed; and which may be positioned so as to lie in the same plane as its associated table sections.

Other objects and advantages of the invention will be particularly set forth in the claims and will be apparent from the following description, when taken in connection with the accompanying drawings, in which:

Fig. 1 is a side elevation of a medical examination table in one position with the knee rest of the invention arranged to support a patient in the kneeling position;

25 Fig. 2 is a view similar to Fig. 1 showing the table in the position conventionally used by proctologists for examination or treatment;

Fig. 3 is an enlarged view of a portion of the table of Fig. 1 showing the knee rest with its cover plate removed for clarity;

30 Fig. 4 is a fragmentary sectional view taken substantially along line 4—4 of Fig. 3 in the direction indicated by the arrows;

Fig. 5 is an end view partially in section of the table portion of Fig. 3;

35 Fig. 6 is a view similar to Fig. 3 showing the leg rest in its lowermost position;

Fig. 7 is a view similar to Fig. 3 indicating how the knee rest is released and swung to the position where it lies in the same plane as its associated table sections to form an extension;

Fig. 8 is a partial view of the table of Fig. 1 with the knee rest forming an extension of its associated table section; and

40 Fig. 9 is an enlarged view of a portion of the table of Fig. 8 including the knee rest.

The knee rest of this invention is particularly adapted for use with the medical examination table described in Patent No. 2,764,459 mentioned above, and, as shown in the drawings, the knee rest has been shown as a component of such a table. However, the knee rest is not necessarily limited to use with this type of table as it may be adapted to any other type of medical table in which it is desired to support the patient in a kneeling or other position and where it is desirable that adjustments be made while the patient is in the supported position.

45 Referring now to Figs. 1 and 2, the knee rest of this invention is incorporated in a medical examination or operating table of the type described in the above mentioned patent which is generally designated by the numeral 11. The table 11 comprises a main table section 12, a leg rest section 13, a head rest section 14 and a supporting base 16. The main table section 12 is pivotally mounted at one end on a pair of cradle members 17 which are carried by a bracket 18 supported on the base 16. The head rest section 14 may be adjustably positioned along the main table section 12 by means of indexing tracks 15.

50 The other end of the main table section 12 is supported on arms 19 which are connected for sliding movement to the table section by means such as a pin and

slot joint designated generally by the numeral 35. It will be particularly noted that the leg rest section 13 and the main table section are not pivotally connected. The arms 19 are secured to the supporting bracket 18 while the cradle members 17 may be pivoted on the support bracket, as indicated at 20, by means of an hydraulic cylinder 21. The leg rest section 13 is pivotally mounted at the opposite end of the cradle members 17 from the main table section 12, as indicated at 25, and may be manually secured in any desired angular position by means of a locking lever 22 which cooperates with a telescopic connection between the cradle members 17 and the free end of the leg rest section 13. A knee rest 23 constructed in accordance with this invention is shown associated with the leg rest section 13.

All of the table sections may be moved vertically to the desired height by an hydraulic mechanism (not shown) contained within the supporting base 16 and operated by means of the control levers 24.

By way of illustration as to how the examination table 11 operates, when the table is in the position of Fig. 1 the patient mounts the table in a kneeling position on the knee rest 23 with the lower front portion of his body in contact with the leg rest section 13. The patient then bends his body forward over the top 26 of the leg rest section 13 in what might be termed a "jack knife" position. Assuming the table is at the general height level desired by the doctor, the hydraulic cylinder 21 may then be operated by means of the controls 24 to pivot cradle members 17 into a position such as that shown in Fig. 2. It will be noted in Fig. 2 that the free end of the main table section 12 has moved somewhat below the top edge 26 of the leg rest section 13 with the result that the upper part of the patient's body will extend downward at an angle. Of course, by means of locking lever 22, the angular position of the leg rest section 13 with respect to the main table section has been preset but normally the right angle relation of the sections is employed. However, regardless of the particular angle chosen, the upper edge or top 26 will always lie above the free end of the main table section 12 as shown in Fig. 2.

This particular movement of the articulated table shown in Fig. 2 and described has been found necessary or at least extremely desirable in proctology and similar types of medical treatment. This position is advantageous in cases where, for example, it is desired to use such instruments as a sigmoidoscope when the patient is located in the position on the table shown in Fig. 2. The patient's stomach muscles are relaxed somewhat into the space indicated at 30. His internal organs are moved into a proper position by gravity to permit insertion of a sigmoidoscope easily and reduce the hazard of puncturing the intestines.

It is highly important, however, that the patient's body lie when bent over the top 26 of the leg rest section 13 in such a way to release and relax the organs. The knee rest 23 must, therefore, be positioned along the leg rest 13 in accordance with the length of the patient's legs. In the previous construction, as shown in the above patent, it was often necessary that a trial and error method of adjustment be used requiring the patient to mount the table with his knees on the knee rest a number of times until the proper position of adjustment could be obtained. In so far as is known, none of the previous constructions permitted the knee rest to be adjusted with the patient in the examination position (see Fig. 2) on the table.

Furthermore, when the table was pivoted to the position of Fig. 2 for examination, and treatment had started, it often was necessary during the progress of the treatment to shift the position of the patient so as to adjust relationship of the knee rest and the top 26 to enable the physician more conveniently to perform his tasks.

Shifting of the patient at this stage of the operation or treatment by making adjustments of the knee rest became highly inconvenient if not impossible because the doctor had to bodily lift the patient. Almost invariably the doctor either compromised by continuing the treatment or operation with the patient in an unfavorable position or it was necessary to shift the table to the position of Fig. 1 and have the patient dismount to enable adjustment of the knee rest.

With the novel construction of this invention, the knee rest 23 has been so arranged that adjustment of its position on its associated leg rest section 13 may be made while the full weight of the patient is supported eliminating the need for removing the patient once he has mounted the table.

As specifically illustrative of the invention, the knee rest 23 comprises a cushion 27 to which is secured by means such as screws 28, a pair of support arms 29, 31. These support arms 29, 31, extend outwardly from the cushion 27 to thickened portions or support arm sections 32, 33 respectively which form a yoke, such as shown in Fig. 5, and are suitably spaced to loosely accommodate the leg rest section 13 therebetween. As the two support arms 29, 31 are substantially identical in structure only support arm 29 will be described hereinafter.

In order to support the knee rest 23 on the leg rest section 13, a guide track, designated generally by the numeral 34, is secured by means such as screws 36 along each side of the leg rest section 13 and extend longitudinally therewith. As shown best in Fig. 4, each track 34 contains a lower rail 37 and an upper rail 38 with which a gear rack 39 is preferably integrally formed.

The inner face of the thickened arm portion 32 has been cut away at 41 to accommodate upper and lower rollers 42, 43 (Fig. 4) which are suitably secured to portion 32 by means such as bolts 44. These rollers 42, 43 are spaced longitudinally of the track 34, as shown best in Fig. 3, so that the upper roller 42 rides on upper rail 38 and the lower roller 43 rolls on the lower rail 37.

Means have been provided to move the knee rest 23 along the guide tracks 34 in accordance with the leg length of the patient who is to be mounted on the table. More specifically, a pinion 46 is connected to a spur gear 47 which is suitably journaled within an opening 48 in the support arm section 32. The pinion 46 is arranged to drivably engage with the rack 39 on the upper guide rail 38 as shown best in Fig. 5. The support arm section 32 is suitably recessed on its outer face at 49 to accommodate the spur gear 47 and a driving gear train connected thereto consisting of gears 51, 52 and 53, rigidly mounted upon shafts 54, 56 as shown. Gear 53 meshes with the end of an elongated drive gear 57 extending between the support cross sections 32, 33. The gear 57 is journaled in any suitable manner at one end in section 33 and at its other end is provided with an integral extension 60 supportedly engaged with an externally threaded tapered slotted bearing 55 fixedly mounted by means such as bolts 50 on arm section 32. A nut 58 is threadedly positioned on the bearing 55 to permit adjustment of the frictional force between the bearing and extension 60. It should be understood that driving gear 57 is drivably connected to a gear train in arm section 33 in a manner identical to arm section 32 so that both pinions 46 are driven along their respective tracks 34.

Each of the support arm sections 32, 33 is provided with a cover plate 61 suitably supported on their outer faces of the sections. The cover plate 61 contains an opening 65 to accommodate the gear extension 60. Extension 60 is provided with a flat 62 and supports an operating crank arm 63 secured thereto by means such as a set screw 64. The arm 63 preferably contains a retractable hand grip 66 to facilitate rotating the gear 57.

It should be understood, however, that although a manual operating arm 63 has been shown for rotating the gear 57, the gear may be driven if desired by an electric motor or the like.

It should be particularly noted and it is one of the important aspects of this invention when the knee rest 23 is positioned, as shown in Fig. 5, with the upper and lower rollers 42, 43 in sliding engagement with the upper and lower rails 38, 37 on track 34, that the pinion 46 is held in meshing engagement with rack 39 and does not contact the inner surface of rail 37. It can be seen in Fig. 3 that when the leg rest 23 is in the operating position perpendicular to the leg rest section 13, it is supported by contact of the rollers on opposite sides of track 34 with the forces being exerted in opposite directions.

In the operation of the table 11, together with the invention, the patient mounts the table by kneeling on the knee rest 23 with the lower part of his body in contact with the leg rest section 13. As previously discussed, the patient bends over the top 26 of the leg rest 13 and the table may then be tilted to the position of Fig. 2. However, it is necessary to insure that the bending of the patient's body is at the proper position longitudinally so adjustment is made in the position of the knee rest 23 while the patient is supported thereon by rotating the hand crank 63 in the proper direction. This moves the knee rest 23 longitudinally of the leg rest section 13 as indicated by the double arrow H in Fig. 1 through the rotation of the pinion 46 along the rack 39 until the proper position of the patient is obtained. It should be understood that the weight of the patient does not affect the movement of the knee rest as the rollers 42, 43 permit the pinion 46 to move easily along track 34 even though the patient may be relatively heavy.

Another of the advantages of the construction of the knee rest is that no positive lock need be provided for any knee rest position selected. The frictional forces in the knee rest gear trains and the additional frictional holding force exerted on the gear extension 60 by the adjustable bearing 55 produces a total holding force of sufficient magnitude to securely hold the knee rest in the adjusted position when the crank is released. In explanation of this fact it will be noted that a load on the knee rest tends to force the knee rest toward a non-right angle relation with respect to the leg rest section. This causes a force on the upper roller 42 in a downward direction (as viewed in Fig. 3) and a force on the lower roll 43 in an upward direction. The action of these forces is such as to tightly grip the rail so that the gripping action increases as the weight on the knee rest increases. As there is a tendency for the knee rest to slide down due to the practically frictionless rollers 42, 43, the frictional forces described as necessary to overcome this movement.

Another of the outstanding features of the invention is the provision by which the knee rest 23 may be quickly and easily detached from the leg rest section 13 and suitably stored until its use is required. To detach the knee rest, the crank 63 is rotated in a counter-clockwise direction as viewed in Fig. 1 to move the knee rest upwardly. The pinion 46 travelling along rack 39 will eventually reach the top end of track 34 and can be easily disengaged from the rack permitting the knee rest to be removed. It can easily be seen that with the novel construction of the knee rest, the detaching of the knee rest from the leg rest 13 may be easily accomplished as the rollers 42, 43 do not interfere in any way. No other parts need be removed nor is any elaborate disassembly required.

It is necessary to provide a limit stop for the downward adjustment of the knee rest 23 for leg lengths. Continuous movement of the knee rest toward the lower end of the leg rest section would result in the upper roller 42 eventually leaving the upper rail 38 permitting

the knee rest to swing in the direction of arrow I as shown in Fig. 7 if such provision were not made. In order to prevent this occurrence, the upper rail 38 on each track 34 is provided with a depression 74 and the lower rail 37 with a notch 76. Each of the support arm sections 32, 33 contains an inwardly projecting pin 77 so that when the knee rest 23 is moved to the position of Fig. 6, the upper roller 42 will fall into the depression 74 and the pin 77 will slip into the notch 76 with a resultant slight canting of the knee rest from the perpendicular. This position therefore represents the maximum leg length adjustment for the knee rest. However, the knee rest is releasably locked in this position, as the parts described have interlocked by virtue of the canting of the knee rest brought about by its own weight alone or together with the weight of a patient. The knee rest may be released by merely tilting it back to the perpendicular and cranking it to the desired position.

Often it is desirable in examination tables of the type described to provide an arrangement whereby such a knee rest may be moved into the same plane as the leg rest section with which it is associated. This feature increases the overall length of the table and permits the table to be used for purposes where a long table is desirable. The novel construction of the knee rest 23 permits this table lengthening feature to be accomplished, as shown in Figs. 7-9.

To locate the knee rest 23 in the table lengthening position of Figs. 8, 9, the knee rest is rotated back to the perpendicular position from the locking position of Fig. 6 and cranked further downward until it can be swung in the direction of arrow I as shown in Fig. 7. The upper roller 42 moves over and around the end of rail 38 while the pin 77 is withdrawn from the end of track 34. As the knee rest is swung further, the lower roller 43 supportingly engages the lower rail 37 as before and the shoulder in recessed portions 41 in the sections 32, 33 engage the upper rail 38 to provide a point of support 78 for the knee rest. The final position of the knee rest is shown clearly in Fig. 9 (in the same plane as the leg rest section 13) and it will be noted that the pinion 46 remains engaged with its rack 39. In addition the knee rest 23 is prevented from moving off the end of track 34 by a stop 79 suitably secured between the rails 37, 38 and containing a forward beveled edge 80 which engages the pinion 46 to limit its movement at the lower end of the track 34.

While the preferred form of the invention has been shown and described, it will be apparent that various changes and modifications may be made therein, particularly in the form and relation of parts, without departing from the spirit of the invention as set forth in the appended claims.

We claim:

1. In a medical examination and operating table, the combination of a leg rest section and a knee rest section, a track on said leg rest section, at least two rollers carried by said leg rest section and engaging said track on opposite sides thereof for supporting said knee rest section in approximately right angle relation to each other, said leg rest section when the table is oriented for some uses extending in a downward direction, said track being open at its upper end so that the rollers may roll off the track without interference whereby the knee rest section can be freely separated from the leg rest section and stop means at the lower end of said track.

2. A table in accordance with claim 1 in which means are provided at the lower end of the track for rendering said stop means ineffective and means are provided enabling movement of the roller on the side of the track toward said knee rest to be shifted out of engagement with the track while the other roller remains in engagement with the track and assists in supporting said knee rest section in planar relation to said leg rest section.

3. A table in accordance with claim 1 in which a rack, a pinion engaging said rack and gearing are provided for shifting said knee rest along said track and means are provided for adjusting the friction in said gearing.

4. In a medical examination and operating table, the combination of a leg rest section and a knee rest section, a track on said leg rest section, at least two rollers carried by said leg rest section and engaging said track on opposite sides thereof for supporting said knee rest section in approximately right angle relation to each other, said leg rest section when the table is oriented for some uses extending in a downward direction, a rack on said leg rest section, a pinion engaging said rack, means including a train of gears and a hand operated crank for driving said pinion and an adjustable friction device between said crank and said pinion.

5. A table in accordance with claim 1 in which the roller engaging the side of the track toward the knee rest is located closer to the lower end of the track than the other roller.

6. A table in accordance with claim 1 in which the roller engaging the side of the track toward the knee rest is located closer to the lower end of the track than the other roller and stop means are provided adjacent the lower end of the track.

7. In a table structure, the combination of a leg rest and a knee rest, means for supporting said knee rest on said leg rest in substantially right angle relation, means for adjusting said knee rest along said leg rest while maintaining said right angle relationship and means between said knee rest and said leg rest for locking said knee rest in any desired position of adjustment along said leg rest, said locking means including means for increasing the locking effect of said locking means as the weight on said knee rest is increased, said last mentioned means comprising a pair of rollers and rail means upon the opposite sides of which said rollers ride, said rollers being arranged so that a weight on said knee rest causes both rollers to exert a pressure on said rail means directed toward said rail means and substantially at right angles thereto.

8. In a medical examination and operating table the combination of a leg rest section and a knee rest section,

5 a track on said leg rest section, means carried by said knee rest section engageable with said track for supporting said knee rest section in approximately right angle relation to said leg rest section, said means comprising at least two rollers, one of said rollers engaging the lower side of said track and the other of said rollers engaging the upper side of said track, said rollers being spaced along said track with the upper roller spaced further along said track from the point of application of a load on said knee rest than the lower roller.

10 9. In a medical examination and operating table the combination of a leg rest section and a knee rest section, a track on said leg rest section, means carried by said knee rest section engageable with said track for supporting said knee rest section in approximately right angle relation to said leg rest section, said means comprising roller means engaging opposite sides of said track, a rack adjacent said track, and means including gearing carried by said knee rest section and engageable with said rack for shifting said knee rest section longitudinally of said leg rest section in either direction with a patient kneeling on said knee rest section.

15 10. In a medical examination and operating table the combination of a leg rest section and a knee rest section, a track on said leg rest section, means carried by said knee rest section and engageable with said track for supporting said knee rest section in approximately right angle relation to said leg rest section while enabling said knee rest section to be freely shifted longitudinally of said track, said means comprising at least two rollers spaced longitudinally of the track with the roller on the upper side of the track being closer to the lower end of the track than the roller on the lower side thereof, and cooperating means between said knee rest section and said track for locking said knee rest section against movement off the lower end of said track.
